UNITED STATES PATENT OFFICE.

WILLIAM SUTCLIFFE, OF PATERSON, NEW JERSEY.

STEAM-ENGINE.

SPECIFICATION forming part of Letters Patent No. 729,107, dated May 26, 1903.

Application filed August 2, 1902. Serial No. 118,046. (No model.)

To all whom it may concern:

Be it known that I, WILLIAM SUTCLIFFE, a citizen of the United States, residing in Paterson, in the county of Passaic and State of New Jersey, have invented a certain new and useful Improvement in Steam-Engines, of which the following is a specification.

This invention relates to the construction and arrangement of parts in a compound engine, and more particularly to the valve gear or mechanism by which motion is imparted to the valves.

The object of the invention is to simplify the valve-gear and provide a construction which shall be efficient, durable, and not liable to derangement.

The invention consists in certain details of construction and arrangements of parts to be hereinafter described.

The accompanying drawings form a part of this specification and show the invention as I have carried it out.

Figure 1 is a side elevation, partly in vertical section, showing a double compound engine embodying my invention. Fig. 2 is a corresponding front view with certain parts removed; and Fig. 3 is a corresponding end view or plan, partly in horizontal section. Fig. 4 is a horizontal section and plan view showing a portion of the valve-gear on a larger scale. Fig. 5 is a side view showing a detail of construction.

Similar letters of reference indicate the same parts in all the figures.

I will describe the invention as applied to a double compound engine especially designed for motor-vehicle service, consisting of four cylinders arranged side by side with their axes in the same plane, the high-pressure cylinders A' A² being adjacent to each other and between the low-pressure cylinders A³ A⁴. The four cylinders, with their cross-head guides A⁵ A⁶ and supports A⁸ for the main shaft C, are preferably formed in a single casting and are so shown in the drawings. The rear heads A¹⁰ and A¹¹ for the high and low pressure cylinders, respectively, are removable and are held in place by studs and bolts, as usual.

A steam-chest D' for each high-pressure cylinder and a steam-chest D² for each low-pressure cylinder are mounted upon the front

faces of such cylinders and are closed by the chest-covers D³ D⁴, secured to the chests and cylinders by studs D⁵. The valve-seats are 55 plane and provided with slide-valves D⁶ D⁷, operated by valve-stems D⁸ D⁹, extending through stuffing-boxes D¹⁰ on the steam-chests, as usual. All the valve-seats are in the same plane, and the D-valves are so constructed as to bring all the stems in the same vertical plane with each other.

On the uppermost of each pair of guides A⁵ A⁶ is cast an upwardly-projecting lug or arm having a rectangular head A⁹, finished 65 interiorly to receive and guide a rectangular block E, parallel and in line with the valve-stem for its respective cylinder, and is joined to its stem by a bar E', keyed thereto and flexibly connected by a joint e to the sliding 70 block E.

The pistons are of any ordinary or approved construction adapted to be reciprocated in the cylinders by the action of the steam or other elastic medium employed. Only one—the 75 low-pressure piston F²—is shown, with one of the piston-rods F⁴. The piston-rods extend through stuffing boxes and glands on the closed front heads of the several cylinders and join the cross-heads B⁴, only one being 80 shown, by any suitable connections.

The shaft C, with the cranks C', C², C³, and C⁴, is preferably sectional, as shown. Each pair of cranks is opposite to another and all are quartering, as shown. The shaft is rev- 85 olubly held to the arms A⁸ by straps A¹², partially encircling the shaft and secured to the arms by gib and keys. The straps and arms may be equipped with brasses, if preferred.

G', G², G³, and G⁴ are connecting-rods from 90 their respective cross-heads to the cranks and join the latter by solid ends, as shown.

I provide a valve motion for each cylinder and connect them together to be operated by a single lever. (Not shown.) A transverse 95 rod A¹⁵ extends across below the cylinders, supported at each end in lugs A¹⁴ on the under side of each low-pressure cylinder. The rod carries four downwardly-extending links J⁴, one beneath each cylinder, forming part 100 of the motion. The latter is arranged in two sets joined together, one for each pair of cylinders, and as each set is a counterpart of the other a description of one will suffice. The

links J^4 are knuckled to the lower ends of a pair of swinging levers K^2 , the upper ends of which are bifurcated at k^2 and inclose each its corresponding connecting-rod at about the 5 mid-length of the latter and are pivotally secured thereto by pins k^4 . Below each junction is set a pin K^4 , on which are centered the links L^2 , the upper ends of which are pivoted at l^2 to the ends of a pair of upwardly-extending rods M^2 , the upper ends of which are knuckled to the lower ends of the slide-blocks E , free to reciprocate in the heads A^9 , as before described.

A^{16} is a lug on each arm A^8 , carrying a short 15 transverse shaft R , carrying on its overhung ends two upwardly-extending arms R^2 , to which are pivotally connected the links O^2 by means of a short transverse shaft N , also carrying a hub or collar P , lying between the 20 links R^2 , and having an arm or reach-rod P' adapted to be engaged by any suitable connection to the corresponding reach-rod of the other set and both sets operated by a single hand-lever located at any convenient point. 25 The links O^2 extend downwardly and are pivotally connected to the links L^2 at the points l^4 below the pins l^2 . The shaft N , through its connections to the reverse-lever, (not shown,) may be moved inwardly or outwardly about the shaft R as a center and the valves correspondingly moved into such relation to the other parts of the motion as to turn the main shaft C forward or backward, as required.

35 The operation of the valve-motion is as follows: Referring for convenience of description to one side of one set, the reciprocation of the cross-head B^4 in combination with the rotary motion of the crank C^4 induces a gyroscopic movement of the point k^4 and causes it to move in an elliptical path. The pin K^4 describes a somewhat similar but shorter ellipse and imparts its motion to the link L^2 , which acts as a lever fulcrumed at l^4 , the short 40 arm of which from l^4 to l^2 produces through its connections a short reciprocating movement of the valve and admits and cuts off steam at the proper intervals. In order to change the position of the point l^4 , and thus 45 allow for changing the direction of the engine, the shaft N , connected to the reverse-lever, (not shown,) may be moved by the reach-rod P' , as indicated. When the parts are in the position shown in Fig. 1, the engine 50 will run to revolve the main shaft in the direction indicated by the arrow, and when moved inwardly to the position indicated by the dotted line X the revolution will be reversed. In both positions the steam follows 55 to the limit provided for by the motion. In approaching the center line X' from either direction the engine cuts off shorter, and when the center of the shaft N coincides with the line X' the cut-off will be at the shortest— 60 about one-tenth of the stroke when proportioned as shown in the drawings. A peculiar 65 advantage of this form of valve-gear is the

uniformity of lead and lap, inside and outside, at all points of expansion. The valve-gear is of simple construction, being composed 70 of simple lever-and-link connections preferably joined by pins to avoid the use of bolts and nuts liable to work loose by vibration and avoids the complications and expensive construction of the usual link-motions. The 75 removal of the valve-gear is effected by taking out the pins connecting the several links J^4 to the levers K^2 , removing the cross-head pins, the shafts N , and the pins at the junctions of the links M^2 with their slides E , and 80 the gibs and keys holding the straps A^{12} to the arm A^8 . The main shaft, with its cranks and connecting-rods and the systems of links and levers constituting the valve-motion, with the exception of the short shafts R and arms 85 R^2 , may be then all taken out together for inspection or repairs and again replaced.

The several pins and short shafts are held against accidental displacement by split keys W , inserted therein and partially received in 90 corresponding retaining-washers W' , as shown in Fig. 5.

In order to resist side strains in the valve-motion, the outer end of each lever K^2 is forked, as shown in Fig. 4, to give the pins k^4 95 substantial bearings on each side of the main connecting-rods, and thus relieve the pins from strains tending to induce friction and wear.

Although I have described the invention 100 as adapted to serve in motor-vehicles and similar situations, it will be understood that it will serve successfully in locomotive or marine or stationary engineering under any conditions to which it may be adapted.

105 All the parts and equipments not specifically described may be understood to be of any ordinary or approved construction.

I claim—

1. The combination of the valve-motion described consisting of the links J^4 , levers K^2 connected thereto and to the main connecting-rods of an engine, the levers L^2 and links O^2 and arms R^2 , and rods M^2 , slide-blocks E and connections from the latter to the valves, 115 with an engine-frame having the lugs A^{15} , A^9 and A^{16} carrying said motion, all substantially as herein specified.

2. The valve-motion described consisting of the links J^4 , levers K^2 connected thereto 120 and to the main connecting-rods of an engine, the levers L^2 and links O^2 and arms R^2 , and rods M^2 , slide-blocks E and connections from the latter to the valves, in combination with the cylinders, guides, and shaft-supporting 125 arms of a compound engine all in a single casting and having the lugs A^{15} , A^9 and A^{16} cast integral therewith and carrying said motion, all substantially as herein specified.

3. In a valve-motion for steam-engines, the 130 link J^4 pivotally joined at one end to the engine-frame, the lever K^2 pivotally connected to the other end of said link and having the forked end k^2 and pin k^4 by which it is con-

5 nected to the main connecting-rod received in said fork, the pin K¹ on said lever carrying one end of a link L², the pin L² at the other end of the latter and connections therefrom to the valve, the pin L⁴ and shaft N, and link O² between them, the arm R² pivotally connected to the engine-frame at one end and at the other to said shaft N, and means for moving the shaft N to control the direction and 10 extent of movement of said valve, all com-

bined and arranged to serve substantially as herein specified.

In testimony that I claim the invention above set forth I affix my signature in presence of two witnesses.

WILLIAM SUTCLIFFE.
